UNITED STATES PATENT OFFICE.

ROSCOE BEAN AND ARTHUR W. GRANT, OF SPRINGFIELD, OHIO, ASSIGNORS
TO THE TRICYCLE MANUFACTURING COMPANY, OF SAME PLACE.

VEHICLE-WHEEL.

SPECIFICATION forming part of Letters Patent No. 319,777, dated June 9, 1885.

Application filed May 5, 1885. (No model.)

To all whom it may concern:

Be it known that we, ROSCOE BEAN and ARTHUR W. GRANT, citizens of the United States, residing at Springfield, in the county of Clark and State of Ohio, have invented certain new and useful Improvements in Vehicle-Wheels, of which the following is a specification, reference being had therein to the accompanying drawings.

10 This invention relates to certain new and useful improvements in vehicle-wheels, and it has for its objects, first, to provide hub-sections adapted to be mounted upon a connecting tube or sleeve, and consisting of a body or ring-like portion having a series of radially-extending arms formed with lugs on their inner faces, and connected together by a rim, from which extends a lip for each arm, whereby that portion of the spokes which is fitted between the 15 ring-like portions and the lugs on the arms may be effectually prevented from becoming dislodged; second, to provide a sleeve, upon which the hub-sections are to be mounted, with an annular shoulder, against which the sections are to press, by bulging the metal of the 20 tube.

In the accompanying drawings, forming a part of this specification, and on which similar letters of reference indicate the same or corresponding features, Figure 1 represents a diametrical sectional view of a wheel, showing our improved hub-section and connecting-sleeve in 25 section; Fig. 2, a view looking at the inner face of one of the hub-sections; Fig. 3, a like view looking at the outer face thereof, and Fig. 4 an edge elevation of the same.

The letter A designates a metallic tube or sleeve, which is constructed of sheet metal by first taking a blank of the required size and 30 rolling or otherwise forming depressions B on that side which is to be the inner side of the sleeve, by bulging the metal, making a resulting external annular shoulder. This blank is then rolled into tubular form, although it 35 may be rolled into that form during the same operation by which the shoulders are made. By this means we have ascertained that a light and cheap sleeve may be manufactured, and one that will not require boring or reaming

out so as to properly finish it for the reception 5c of the axle-spindle.

The letter D designates the body or inner ring-like portion of the hub-sections, from which extend, from points around its periphery, any suitable number of radial arms, E. On that side 55 of each of which which is toward the center of the wheel is formed a shoulder, G, as clearly seen in Fig. 1, whereby a seat is formed between the periphery of the ring-like portion D and said shoulder for the spokes, as will presently 60 appear. These arms are connected at their outer ends by the rim H, the office of which is not only to give strength to the arms by uniting them together, as just observed, but is also to form a surface against which the spokes 65 shall fit, as seen in Fig. 1. From this rim a series of lips, I, project, one lip being at each spoke. These hub-sections are to be made of malleable cast-iron, and the position of the lips I with respect to the rim is that seen in Fig. 4, 70 so that the sections may be drawn from the mold and the necessity of casting with a core avoided. These lips, as seen in Figs. 1 and 2, are bent across the space between the ring-like portion D and the shoulders G of the arms, 75 and serve to keep the spokes more effectually to their seat within said space. We prefer to make the rim H of the form shown—that is, broad and thin—as by this means we unite strength with lightness of weight. The spokes 80 are formed in pairs, each pair being made of one rod or wire, the curved portion J of which is fitted within the spoke-seat, before alluded to, and each of the arms E is embraced by the members of the respective spoke-seats. The 85 ends of the spokes are united to any suitable rim in any approved manner, and the position of the hub-section on the sleeve A with respect to each other is preferably such as to cause the spokes of one set to unite with the rim between 90 the spokes of a set attached to the opposite section. As the spokes in projecting from the hub-sections to the rim are deflected toward each other, it will be observed that when tractive strain is exerted upon them their tendency will be to draw the sections together, and thereby force them firmly against the shoulder C and add rigidity to the structure. 95

Having thus fully described our invention, what we claim as new, and desire to secure by Letters Patent, is—

1. In a wheel, the combination, with a sleeve 5 constructed with bulged shoulders, of the hub-section fitted thereon and consisting of a ring-like portion having shouldered arms, a rim connecting said arm and retaining-lips, and the spokes fitted between the ring and shoulders 10 on the arms.
2. In a wheel, the combination, with a sleeve constructed of sheet metal having bulged shoulders, of hub-sections fitted upon the sleeve and constructed to receive spokes.
- 15 3. In a wheel, the sleeve constructed of sheet metal and having bulged shoulders.

4. In a wheel, a hub-section constructed of a body or ring-like portion, radial arms extending therefrom, having shoulders, whereby spoke-seats are formed between the periphery 20 of the ring and the shoulder, and a rim connecting said arms together provided with lips.

5. In a wheel, a hub-disk having spoke-retaining lips constructed to be bent across the spoke-seats.

In testimony whereof we affix our signatures in presence of two witnesses.

ROSCOE BEAN.
A. W. GRANT.
